and Rudolph G. Blaho, Franklin Park, Ill., assignors to
Arnold, Schwinn & Co., Chicago, Ill., a corporation
of Illinois

Filed Nov. 9, 1966, Ser. No. 4,600

Term of patent 14 years

(Cl. D90—11)

FIGURE 1 is a perspective view of a twin control lever assembly for bicycles embodying the features of our invention, with parts of a bicycle shown in broken lines to illustrate the location thereon for mounting the same;

FIG. 2 is a top plan view;

FIG. 3 is a rear elevation with the upper portions of the levers broken away merely for convenience of illustration;

FIG. 4 is a side view, with adjacent parts of the bicycle being shown in broken lines; and

FIG. 5 is a front elevational view, as seen from the right side of FIG. 4.

The broken line showings are for illustrative purposes only.

We claim:

The ornamental design for a twin control lever assembly for bicycles, as shown and described.
